BAND-PASS INPUT CIRCUIT

Emmery J. H. Bussard, Cincinnati, Ohio, assignor
to Avo Manufacturing Corporation, Cincinnati,
Ohio, a corporation of Delaware

Application January 3, 1949, Serial No. 68,771

1 Claim. (Cl. 250—20)

1

The present invention relates to antenna input circuits for radio receivers.

The primary object of the invention is to provide a radio frequency input circuit which requires no manual tuning operations but which covers a wide frequency band, such as the AM broadcast band (540 kc.—1600 kc.) with high voltage gain for desired signals and great attenuation of undesired signals outside the broadcast band.

Another object of the invention is to provide a fixed-tuned radio frequency input circuit which has substantially uniform transfer constant and voltage step-up characteristics over a wide frequency band, and which at the same time provides desired selectivity and discrimination against image signals and signals of intermediate frequency.

A further object of the invention is to provide an antenna input circuit comprising an auto-transformer, in which a part of the transformer not included in the primary is employed in conjunction with a shunt capacitor as an anti-resonant wave trap to discriminate against undesired signals.

For a better understanding of the invention, together with other and further objects, advantages, and capabilities thereof, reference is made to the following detailed description of the accompanying drawings, in which there are disclosed two illustrative R. F. antenna input circuits in accordance with the invention.

In the drawings:

Fig. 1 is a circuit diagram of a preferred form of radio frequency antenna input circuit in accordance with the invention;

Fig. 2 is a circuit diagram of a modified form in which the antenna loop is employed as the primary;

Fig. 3 is a performance curve showing the response characteristic of the Fig. 1 embodiment; and Fig. 4 is a perspective view of a transformer suitable for incorporation in the Fig. 1 embodiment.

As is well known to those skilled in the art, the radio frequency section of a receiver includes the coupling from the antenna to the grid of the first tube, such coupling being generally referred to as the antenna input circuit. The chief purposes of this circuit are to provide selectivity against image and intermediate frequency and

2

other interfering signals and at the same time to afford voltage gain between the antenna and the grid-cathode input circuit of the first R. F. amplifier tube. It is customary to provide a tuned radio frequency stage between the antenna input circuit and the mixer or frequency converter, or a tuned antenna input circuit coupled to the converter. Capacitors or inductors in both the antenna input circuit and the oscillator tank circuit are adjusted to select the desired signal channel. However, when push-button tuning or equivalent automatic selector arrangements are employed, it is desirable to omit the adjustments of the antenna input circuit and to provide a band pass antenna input circuit which passes signals within the entire band under consideration, such as the AM broadcast band, with substantially uniform voltage step-up characteristics over the entire band, and also with the required selectivity and discrimination performance characteristics.

To provide such a circuit has for a long time posed a very difficult problem, and the need for a simplified push-button tuning system has prompted many endeavors to solve it.

Referring now specifically to Fig. 1 of the drawings, there is shown a low impedance loop antenna 11 and a converter tube 10. The purpose to which the present invention is directed is to couple the loop to the control electrode of converter tube 10 in such a way as to eliminate the conventional antenna input variable tuning and at the same time to meet the performance requirements mentioned above. The performance equivalent of an over-coupled double-tuned transformer has been provided by the invention. Loop 11 is shunt-connected to primary 13 of auto-transformer 16, and this section of the input system is resonated to about the mid-frequency range by means of fixed capacitor 12. Specifically, the loop 11 and its series tuning capacitor 12 are coupled to the primary 13 of an auto-transformer 16. The primary 13 is tuned approximately to the center of the AM broadcast band, for example, by capacitor 12 in series with low impedance loop 11 and by the distributed capacitance 17 of the loop and primary. The secondary 13, 14, 15 of transformer 16 is tuned by shunt capacitor 18 approximately to the center frequency of the AM standard broadcast band. There are shown in association with the circuit

the usual coupling capacitor 19 and a grid resistor 20 leading to source of AVC voltage (not shown). The elements 19, 20 couple the antenna input circuit to the control electrode of converter 10. Local oscillator voltage is injected in conventional manner through a capacitor 21 coupled to the output of an oscillator (not shown). The low voltage terminals of the loop, coil 13, capacitor 18, resistor 22, and the cathode of tube 10 are grounded at 23.

Portions 14 and 15 of the transformer secondary, together with shunt capacitor 24, comprise a trap circuit which is anti-resonant at the I. F. frequency. In a particular embodiment of the invention which was successfully reduced to practice, the receiver was of the double superheterodyne type and the first I. F. frequency was 5825 kilocycles. The trap circuit comprising secondary portions 14, 15 and capacitor 24 provides very effective discrimination against unwanted signals of I. F. frequencies. The other parameters employed in this illustrative embodiment were as follows:

Inductance of loop 11	micro-henries	15.65	25
Capacitor 12	micro-micro-farads	750	
Distributed capacitance of coil 13	do	11	
Capacitor 18	do	220	
Inductance of coil 13	micro-henries	30	
Sum of inductance of coils 13, 14, and 15 in series and twice the mutual inductance between the primary and secondary	micro-henries	215	
Mutual inductance between primary 13 and secondary 13, 14, 15	micro-henries	38	
Shunt tuning of loop 11	kilocycles	2550	35
Distributed capacitance of loop 11	micro-micro-farads	63	
Resistor 22	ohms	5600	
Tube 10	Type	6AC7	
Resistor 28	megohm	1	40
Capacitor 21	micro-micro-farads	10	

The gain and selectivity of the system can be materially improved by resonating the loop near to the high end of the desired range. 2550 kilocycles proved satisfactory in the example cited. That is, loop 11 and shunt capacitance 17 are preferably resonant at about 2550 kilocycles. Loop 11 and capacitor 12 and primary 13 are resonant at the center of the broadcast band. Resistor 22 is employed to limit the peak gains in such a manner that the gain ratio of peaks to valley is not excessive.

Referring now specifically to Fig. 3 of the drawings, the performance curve there shown illustrates the band pass input gain characteristic of a receiver having an antenna input circuit in accordance with the invention and employing the illustrative parameters above mentioned, as compared to a like receiver employing a typical manually tuned input circuit. The response curve is plotted on a system of Cartesian coordinates with frequency in kilocycles as abscissae and gain in decibels as ordinates. It will be observed that the response characteristic is indicative of a double-tuned over-coupled system, one "hump" occurring at about 660 kilocycles and the other at about 1250 kilocycles. This gain characteristic curve indicates a uniformity which is commercially acceptable throughout the standard broadcast band. Such results cannot be achieved by conventional methods of coupling. A coupling coefficient on the order of 0.55 is required for coverage of the AM broadcast band, for example.

Sensitivity measurements of a receiver with these illustrative parameters give the following results:

Frequency in Kilocycles	Input	Output
	<i>Micro-</i> <i>volt</i>	<i>Watts</i>
550	6.8	1
600	3.6	1
650	2.0	1
700	2.4	1
750	3.4	1
800	4.2	1
850	4.9	1
900	4.8	1
950	4.9	1
1,000	4.7	1
1,050	4.4	1
1,100	4.0	1
1,150	3.3	1
1,200	2.1	1
1,250	1.8	1
1,300	2.8	1
1,350	5.3	1
1,400	8.5	1
1,450	11.8	1
1,500	15.6	1
1,550	20.5	1
1,600	29.0	1

In this illustrative receiver the band pass input transformer, as shown in Fig. 4, was wound with 15-strand No. 44 Litz wire in three coils 13, 14, 15, each $\frac{5}{64}$ inch in width, spaced about $\frac{1}{16}$ inch, on a form 25 having a $\frac{3}{8}$ inch diameter. These coils are identical, each having 35 turns.

Referring now specifically to Fig. 2 of the drawings, there is shown an embodiment in which loop 28 is common to both input and output of the coupling network. This coupling arrangement includes loop 28 and series inductors 29 and 30 as the secondary. Loop 28 is the primary of an effectively over-coupled double-tuned system. Like reference numerals are employed to designate elements which are the same as those shown in the Fig. 1 embodiment. In the Fig. 2 embodiment the secondary portions 30 and 29 are shunt-tuned by their own distributed capacitance to provide the anti-resonant trap circuit for I. F. frequency rejection. The loop is tuned by a shunt capacitor 31. The primary is tuned by capacitor 34, and the secondary by capacitor 18, each to the approximate mid-frequency of the band to be received.

The auto-transformer feature provides the required coupling for peak displacement and for uniform voltage step-up. The invention is of particular utility in a double superheterodyne receiver in which the first intermediate frequency is substantially higher than the band to be received. Its use permits the antenna tuning condenser to be omitted, avoids tracking problems, and permits complete range tuning with a very small variable capacitor.

While there have been shown and described what are at present considered to be the preferred embodiments of the present invention, it will be understood by those skilled in the art that various substitutions of equivalents may be made therein without departing from the true scope of the invention as defined by the appended claim.

Having fully described and disclosed my invention, I claim:

In a radio receiver, an antenna input circuit adapted to afford a relatively uniform response throughout the AM broadcast band without manual tuning, comprising a vacuum tube having an input and an output circuit, an input network including a low impedance loop, a high-Q auto-transformer having primary and secondary wind-

ings, a first capacitor coupling said low impedance loop across the primary of said autotransformer so as to form a series resonant network tuned to the mid-frequency of said band, a second capacitor means connected in shunt across that part of the secondary of said autotransformer which is not common to the primary to form a rejector network anti-resonant at the receiver intermediate frequency, a third capacitive means coupled across the end terminals of said autotransformer to series resonate at the mid-frequency of said band the loop circuit in which the third capacitor means is included, and means coupling the input circuit of said vacuum tube across said third capacitive means, whereby a 15 large gain between the low impedance loop and the input of said vacuum tube and a wide band relatively uniform response characteristic is realized, and whereby undesired signals of intermediate frequency are rejected by said anti-resonant rejector circuit. 20
